[57] CLAIM

The ornamental design for a case for a hand-held scanner for personnel identification through retinal blood vessel patterns, as shown and described.

DESCRIPTION

FIG. 1 is a top perspective view of a hand-held scanner for personnel identification through retinal blood vessel patterns showing my new design;

FIG. 2 is a top plan view thereof;

FIG. 3 is a front elevation thereof;

FIG. 4 is a side elevation thereof, the reverse side elevation being the same;

FIG. 5 is a rear elevational view thereof; and

FIG. 6 is a bottom plan view thereof.

FIG. 1

FIG. 2

FIG. 3

FIG. 4

FIG. 6

FIG. 5
